GARMENT WITH DETACHABLE NECKPIECE

David Michel, Chicago, Ill., assignor to Rothmoor Corporation, Chicago, Ill., a corporation of Illinois

Application January 22, 1942, Serial No. 427,681

2 Claims. (Cl. 2-98)

This invention relates generally to articles of wearing apparel, and more particularly to a garment such as a coat or the like having a removable collar or fur neck piece.

The object of this invention is to provide a garment of the character described which is readily convertible from a fur trimmed article of apparel to a simple untrimmed garment, and vice versa.

A further object of the invention is to provide a garment of the character described which will be readily convertible into any one of a variety of different styled articles of apparel, by the mere addition thereto of a different ornamental neck piece.

A further object of the invention is to provide in a garment of the character described a novel and improved construction whereby an ornamental neck piece may be readily attached thereto or detached therefrom.

A further object of the invention is to provide a construction of the character described, whereby the fastening means utilized to attach the ornamental neck piece is concealed when the ornamental neck piece is so attached, or is detached.

A still further object of the invention is to provide a construction of the character described in which the ornamental neck piece will, when attached to the garment, have the appearance of being permanently attached thereto.

A further object of the invention is to provide in a garment of the character described fastening means for the ornamental neck piece which is simple in operation and easily accessible.

A still further object of the invention is to provide a garment of the character described, including a neck band provided thereon and having a concealed portion of a slidable fastening device associated therewith, whereby an ornamental neck piece may be temporarily secured to said neck band, said neck band including a flap member adapted to overlie and conceal said portion of said slidable closure.

A further object of the invention is to provide in a garment of the character described, a construction whereby an ornamental neck piece may be adapted for temporary attachment thereto, said construction including a novel downwardly extending flap affixed to the neck band of the garment and adapted to conceal the attaching means, whether said piece is attached to the garment or not.

Other features of the invention lie in the specific constructional details thereof which lend to a neat, well made, serviceable and practical article of wearing apparel.

5 With the foregoing and other objects in view, which will appear as the description proceeds, the invention consists of certain novel features of construction, arrangement and combination of parts hereinafter fully described, illustrated in the accompanying drawing, and particularly pointed out in the appended claims, it being understood that various changes in the form, proportion, size and minor details of the structure may be made without departing from the spirit or 10 sacrificing any of the advantages of the invention.

For the purpose of facilitating an understanding of my invention, I have illustrated in the accompanying drawing a preferred embodiment 15 thereof, from an inspection of which, when considered in connection with the following description, my invention, its mode of construction, assembly and operation, and many of its advantages should be readily understood and appreciated.

20 Referring to the drawing in which the same characters of reference are employed to indicate corresponding or similar parts throughout the several figures of the drawing:

25 Fig. 1 is a perspective view of the upper portion of a garment constructed in accordance with my invention and having an ornamental neck piece attached thereto.

Fig. 2 is a similar view, but having the neck 30 piece detached from the garment.

Fig. 3 is an enlarged perspective view of the garment showing the neck piece in the process of being detached therefrom.

Fig. 4 is a sectional view taken through the 35 neck band of the garment, generally along the line 4-4 of Fig. 3.

Referring now to the constructional details of the garment, the reference character 10 designates generally the body of an article of wearing apparel, such as, for example, a dress, coat or jacket, with which my invention is adapted to be associated. Obviously the invention is not limited to articles of ladies' wearing apparel, but might even be adapted to men's and children's 45 wearing apparel. In the garment illustrated, there are provided front portions or panels 11 and 12 which are adapted to meet or overlap and be held in such position by the button 13 and the buttonhole 14. At the upper portion of the garment is provided a neck band, generally designated 15, which has the appearance, as shown, of being made up of two somewhat convex portions, an upper portion 16 and a lower portion 17.

When the garment 10 is provided with a neck 50 piece comprising a fur collar 18, it has the ap-

pearance illustrated in Fig. 1, with the neck piece 18 encircling the neck band 15 and overlying the shoulders of the garment 10. As is usual, the fur neck piece 18 is provided with cooperating hook 19 and eye 20 in the front thereof to cause same to be held over the front panels 11 and 12 of the garment.

While a fur neck piece 18 has been illustrated, it should be understood that any type of neck piece may be used. This may include a collar having ornamentations other than fur thereon, constructed of the same material which forms the body of the garment 10, etc. By means of my new invention, even a hood may be attached to the garment.

As shown in Fig. 4, the upper portion 16 of the neck band 15 is permanently fixed in place by means of the row of stitching 21. However, the lower portion 17 is in the nature of a flap extending downwardly from the line of stitching 21. In the embodiment shown, the portion 16 is formed by folding the piece of material which forms the body of the neck band 15 to form the inside face 15' of the upper edge of the neck band, and continuing same downwardly, folding the bottom edge upon itself and stitching same at 21 to form the portions 16 and 17. As shown in Fig. 3, the lower edge 22 of the flap 17 is free about the circumference of the neck band 15, except for a short portion 23 which is attached by the line of stitching 24 at the front of the coat immediately over the buttonhole 14. A similar line of stitching 25 is provided for fastening the edge 26 adjacent the button 13.

Immediately below the flap 17, and concealed thereby, I have provided a portion 27 of a slideable fastener, generally designated 28, such as commonly known as a zipper. Obviously any other applicable slideable fastener means may be used. The portion 27 is held in place upon the portion 29 of the neck band 15 and is attached to the inner face 15' by means of lines of stitching 30, as shown. It will be seen from Fig. 2 that when the fur collar 18 is not attached to the garment, the flap 17 overlies the half 27 of the slideable fastener 28 and conceals same from view. In this condition the garment 10 presents the appearance of a neat sport style jacket, coat or dress.

The fur neck piece 18 is provided with the members 31, preferably formed of the same material from which the coat body 10 is made, attached to same by the lines of stitching 32. Obviously, although not shown, the collar backing may include suitable stiffening members, felting, linings, etc., same being omitted for purposes of clarity. At the outer edge of the member 31, I have attached the second half portion 33 of the slideable fastener 28, affixed thereto by the row of stitching 34. It is preferred that the half portion 33 be attached in such a manner that only a small portion of the teeth of the slideable fastener 28 extends therefrom.

From the above description, it will be seen that the collar 18 may be attached to the coat 10 in a simple manner. By means of the slideable member 34 the half portions 27 and 33 of the slideable fastener 28 are caused to cooperate about the circumference of the neck band 15, thereby fastening the collar 18 upon the coat 10 and giving same the appearance illustrated in Fig. 1. During the attaching process, the flap 17 is lifted and immediately after the collar has been attached said flap 17 may be bent downward to

cover the entire slideable fastener 28, thereby concealing same from view.

Because of this construction, that is, with the flap 17 attached along the line of stitching 21 and extending in a downward direction, it is almost impossible for same to gape or fall open, or be bent to expose the slideable fastener 28 when the neck piece 18 is attached or to expose the half portion 27 when the neck piece 18 has been removed.

Inasmuch as the fur piece 18 is attached to the coat along its upper edge, same will hang in a natural manner and not give the appearance of being temporarily attached to the coat.

15 If desired, a plurality of various styles or types of neck pieces may be sold with the single garment 10, thereby making same available for a variety of neck piece styles.

It will be seen from the above description that 20 the construction of my invention is simple and easily adaptable to almost any style of garment. In view of this, it is practical to adapt all manner of wearing apparel to the expedient taught by my invention.

25 It is believed that my invention, its mode of construction and assembly, and many of its advantages should be readily understood from the foregoing without further description, and it should also be manifest that while a preferred 30 embodiment of the invention has been shown and described for illustrative purposes, the structural details are nevertheless capable of wide variation within the purview of my invention as defined in the appended claims.

35 What I claim and desire to secure by Letters Patent of the United States is:

1. In a garment of the character described, a body portion, a neck band provided on the upper edge of said body portion and including a cloth member doubled upon itself and forming inner and outer faces of said neck band, the outer face being substantially divided in two by a circumferential row of stitching, forming upper and lower portions, the lower portion being doubled upon itself and thereby forming a free edge whereby same comprises a downwardly depending flap, a portion of a slideable fastening device attached to said garment beneath said flap and concealed thereby and a neck piece having the second portion of said slideable fastening device attached thereto and adapted for cooperation with said first portion whereby said neck piece may be secured to said garment about the neck band thereof.

55 2. In a garment of the character described, a body portion, a neck band provided on the upper edge of the body portion and including a cloth member formed with upper and lower halves separated by a line of stitching said

60 halves having the same outward appearance, but said lower portion being a downwardly extending free-edged flap, a portion of a slideable fastening device attached to said neck band immediately beneath said flap and adapted to be concealed thereby, and a neck piece being provided

65 with the cooperating portion of the slideable fastening device and adapted to be detachably secured to said neck band thereby, said neck band having means normally tending to hold said flap in a position concealing said fastening device, comprising a line of stitching holding a portion of the free edge of said flap to said neck band.
